UNITED STATES PATENT OFFICE.

YANCEY Q. CALDWELL, OF PARIS, TENNESSEE.

PADLOCK.

No. 828,919.

Specification of Letters Patent.

Patented June 19, 1906.

Application filed August 25, 1905. Serial No. 275,788.

To all whom it may concern:

Be it known that I, YANCEY Q. CALDWELL, a citizen of the United States, residing at Paris, in the county of Henry and State of Tennessee, have invented new and useful Improvements in Padlocks, of which the following is a specification.

This invention relates to locks having means directly operative by a separate element or key to actuate a sliding bolt or shackle with respect to a staple or other analogous coöperating device and wherein the use of resilient and delicate members is completely avoided.

The improved features are preferably embodied in the form of a padlock, but may be utilized in a trunk, mortise, or other lock. The number of necessary parts is reduced to a minimum, and consequently the general structure is rendered strong and durable. It is almost impossible to pick the improved lock, owing to the particular construction thereof and the required operation of the means for actuating the bolt or shackle by a key.

One of the most advantageous features of the lock is the facility with which the several parts may be assembled or disassociated.

The drawings illustrate a preferred embodiment of the invention, and therein—

Figure 1 is an elevation of the improved lock shown in padlock form. Fig. 2 is a plan view of the lock, showing a part of the casing removed, the bolt or shackle being illustrated in retracted position. Fig. 3 is a view similar to Fig. 2, showing the bolt or shackle projected. Fig. 4 is a section on the line 4-4, Fig. 3. Fig. 5 is a detail perspective view of the key. Fig. 6 shows an enlarged detail perspective view of the shackle or bolt and the actuating or controlling device therefor separated.

Similar numerals of reference are employed to indicate corresponding parts in the several views.

The lock-casing is composed of a body 1 and a closing-plate 2 of similar contour, which is removably secured to the body by any suitable means. The upper central portions of the body 1 and plate 2 are formed with coinciding recesses 3 and 4 to receive a staple or analogous device, and to the left of the recess 3 of the body and normally covered by the plate 2 is a seat or slot 5 to receive the free end of the bolt or shackle, which will be hereinafter specified. The body 1 has a

curved cavity 6, which opens into the recess 3 opposite the seat or slot 5. The cavity 6 is enlarged toward its inner extremity and gradually reduced toward its outlet to the recess 3. The closing-plate 2 has an escutcheon 7 secured over a suitable key-opening and located at the center near the lower edge.

The movable elements of the lock consist mainly of a bolt or shackle actuator or controller 8, a bolt or shackle 9, and a pinion 10, the latter being operated by a key 11 to shift the actuator or controller 8 in opposite directions in the cavity 6 to expel or retract the bolt or shackle 9. One end of the actuator or controller 8 is formed with a rounded coupling-head 12, having a transversely-reduced neck 13, formed by curved seats 14 and 15. The shackle 9, which is projectable and retractable through the upper outlet of the cavity 6 to engage with and be withdrawn from the seat or slot 5, has an inner enlarged coupling extremity 16, with a slot 17 therein opening through the inner end to receive the head 12 and neck 13 of the actuator or controller, the said inner enlarged extremity being formed with guards 18 with respect to the slot 17 to engage the reentrant curved seats 14 and 15, forming the neck 13. The head 12 and neck 13 are freely movable in the slot 17 to compensate for variations in the movement of the actuator or controller 8 and the bolt or shackle 9, so as to avoid jamming either of the said latter parts. The actuator or controller 8 and the bolt or shackle 9 may be readily assembled or disassociated through the medium of the coupling-head 12 and its neck 13 and the slot 17, and no other fastening means are required when the said parts are assembled to maintain them in operative relation, thus reducing the cost of manufacture and facilitating the original assemblage of the parts of the lock, as well as their repair when found necessary. A further advantage of this mode of connecting the actuator or controller 8 and bolt or shackle 9 is that either of said parts may be replaced by a new one in the event of breakage without impairing the entire lock structure. The ends of the guards 18 are also rounded, so as to move easily in the seats 14 and 15 and obviate any restriction in the ready or easy movement of the actuator or controller and the bolt or shackle. If the bolt or shackle becomes broken or worn to such an extent that it must be replaced by a new similar part, it is only necessary to remove the plate 2 and elevate the said bolt or

95

100

105

110

shackle out of the cavity 6 and substitute the new one therefor without disconnecting the actuator or controller 8 and then close the lock by resetting the plate 2.

5 The actuator or controller 8, in addition to the head 12 and neck 13 just explained, has a lower elongated curved edge 19, which is held clear of the corresponding curved edge of the cavity 6, and extending longitudinally 10 of the lower portion of the said actuator or controller 8 is a curved slot 20, having its upper shorter wall regularly toothed, as at 21, the lower longer wall being smooth, and projecting through the said slot is a pinion 10, 15 which engages the said upper toothed wall 21 and is insertible into the slot through an enlarged opening 23 at the right end of said slot. The pinion 10 is rotatably held on a post 24, projecting outwardly through the 20 cavity 6 from the rear of the body 1, and the outer end of the pinion has an angular spindle 25 projecting therefrom and provided with a lug 26. The key 11 has a bore 27 in its one end to fit over the spindle 25 and a slot 25 28 to engage the lug 26, and when said key is properly applied the pinion 10 may be rotated in reverse directions to accordingly move or shift the actuator or controller 8. The teeth of the upper wall of the slot 20 are 30 continued through the left terminal or end of said slot, as at 28^a, to always have the pinion in engaging position with respect to the actuator or controller, the curvature of the upper toothed wall 21 of the controller being such 35 as to always maintain the teeth of said wall in positive engagement with the teeth of the pinion 10. Above the slot 20 and in the center of the actuator or controller 8 is a shorter curved slot 29, having its upper wall formed 40 as a cam projection 30, the said projection slidably engaging a pin 31, secured to the rear of the body and projecting into the slot 29. This slot with its cam projection and the pin 31 operate to hold the actuator or 45 controller 8 in such position as to always insure operative engagement of the pinion 10 with the upper toothed wall 21 of the slot 20. At the inner terminal of the slot 29 is an upwardly-projecting locking-seat 32 to receive 50 55 the pin 31 when the actuator or controller is shifted to expel the shackle or bolt into locking position. The function of this seat 32 is to resist movement of the actuator or controller through the exposed portion of the bolt or shackle and the actuation of the pinion without the aid of the key. In other words, this seat 32 and pin when in engagement one with the other form a lock which 60 prevents movement of the shackle by irregular methods when said shackle is in locking position. The slot 29 at its opposite extremity is slightly deflected upwardly to receive the pin 31 and to hold the actuator in such position that the upper toothed wall 21 65 will always practically engage the teeth of

the pinion 10 without binding on the latter and resist accidental disengagement of the said toothed wall and pinion when the actuator and shackle or bolt are retracted and which disengagement might otherwise ensue 70 if the lock were subjected to a sudden jar by falling, particularly after the parts had become slightly worn. The end of the slot 29 opposite that having the seat 32 therein also serves as a stop means for the movement of 75 the actuator and to indicate to the operator when the actuator and shackle or bolt are fully retracted to avoid disengagement of the teeth at the right-end extremity of the wall 21 from the pinion.

80 From the foregoing the operation of the lock will be readily understood, and in various uses it is intended to modify the proportions, dimensions, and minor details within the scope of the invention.

85 Having thus fully described the invention, what is claimed is—

1. In a lock, the combination of a casing, a bolt or shackle, a sliding toothed actuator for and separably connected at one end to the bolt or shackle, and toothed means for shifting the actuator in opposite directions to 90 expel and retract the bolt or shackle.

2. In a lock, the combination of a casing, a bolt or shackle having a coupling-slot at its 95 inner extremity, and sliding actuating mechanism for the bolt or shackle having a coupling-head loosely and removably engaging the said coupling-slot of the bolt or shackle.

3. In a lock, the combination of a casing, a 100 bolt or shackle having a curved slot in its inner extremity, sliding toothed actuating means for the bolt or shackle having a curved coupling-head at one end to loosely and removably engage the said slot, whereby either 105 the bolt or shackle or the actuating means may be replaced by another like part, and a rotary toothed device fitted in and engaging a part of said actuating means.

4. In a lock, the combination of a casing, a 110 bolt or shackle having a slot at its inner extremity with guards on opposite sides thereof, a sliding toothed actuating means having a head loosely and removably disposed in said slot, and opposite seats to receive the 115 guards, and a rotatable toothed device fitted in and engaging a portion of the said actuating means.

5. In a lock, the combination of a casing, a 120 bolt or shackle, an actuator or controller loosely connected to the inner extremity of the bolt or shackle and provided with a lower elongated curved slot with an upper toothed wall and upper shorter curved slot, a pinion fitted in the lower curved slot, and a pin engaging the upper wall of the shorter slot.

6. In a lock, the combination of a casing, a 125 bolt or shackle, an actuator or controller loosely connected at one end to the bolt or shackle and provided with an elongated 130

curved slot having an upper toothed wall, a pinion engaging the slot and held in mesh with the upper toothed wall, and means for rotating the pinion to shift the actuator or controller in opposite directions.

7. In a lock, the combination of a casing, a bolt or shackle, an actuator or controller loosely connected at one end to the bolt or shackle and provided with a curved slot, a pin engaging said slot and operating as a stop means with respect to opposite terminals of said slot, and means for shifting the actuator or controller in opposite directions.

8. In a lock, the combination of a casing, a bolt or shackle, an actuator or controller attached to the bolt or shackle and provided with a curved slot upwardly projected at one extremity to form a seat, a pin projecting through said slot and adapted to engage the said seat to limit the movement of the actuator or controller, and means for operating the actuator or controller.

9. In a lock, the combination of a casing, a bolt or shackle, an actuator or controller connected to the bolt or shackle and provided with a lower elongated curved slot having an upper toothed wall and a shorter curved slot above the former slot, the shorter curved slot having a cam projection at its upper wall and a seat at one extremity, a pin extending through the shorter curved slot and adapted to engage the cam projection and seat, a pinion inserted through the lower longer curved

slot and held in mesh with the upper toothed wall of the latter, and means for operating 35 the pinion.

10. In a lock, the combination of a casing, a bolt or shackle, an actuator or controller connected to the bolt or shackle and having a lower slot with an upper curved toothed wall, 40 the opposite extremities of the latter wall projecting upwardly, said actuator or controller also having a shorter slot above the former provided with a terminal locking-seat, a pin extending through the shorter slot to engage the seat, a pinion fitted in the lower slot and held in mesh with the curved toothed wall of the latter, and means for operating the pinion.

11. In a lock, the combination of a casing, 50 a bolt or shackle, an actuator or controller connected to the bolt or shackle, and provided with a lower curved slot formed with an upper toothed wall and an enlarged opening at one extremity, a pinion inserted 55 through said opening and adapted to be disposed in position through the said slot, and means for operating the said pinion.

In testimony whereof I have hereunto set my hand in presence of two subscribing witnesses.
